GLASS-CLEANING DEVICE

Lawrence Anthony Fleury, Seattle, Wash.

Application August 10, 1948, Serial No. 43,381

3 Claims. (Cl. 15—75)

1

This invention relates to glass cleaning devices and it has reference more particularly to the provision of a practical and conveniently usable means for the cleaning of drinking glasses, such as those used in restaurants, taverns and like places; it being the principal object of the invention to provide a glass cleaning device whereby the inside of a glass may be cleaned by the action of a brush and the outside cleaned and wiped by one or more sponge or foam rubber brushes that better serve to remove finger marks, lipstick and other substances that are difficult to remove or cannot be removed by the usual rinsing in water or light brushing.

It is also an object of the invention to provide a device of the above stated character wherein provision is made whereby the intended manual application of a drinking glass to a bristle brush in a cleaning operation will operate automatically to bring the rubber brushes into contact with the outer surfaces and rim of the glass for their functional operation of cleaning these parts while the bristles cleanse the inner surfaces of the glass.

Another object of the invention is to provide a means of applying the rubber brushes for effectively and quickly wiping lipstick from the rim of the glass, both along the inside and outside thereof.

Still further objects reside in the details of construction of parts, in their combination, and mode of use as will hereinafter be fully described.

In accomplishing the above mentioned and other objects of the invention, I have provided the improved details of construction, the preferred forms of which are illustrated in the accompanying drawings, wherein:

Fig. 1 is a perspective view of a glass cleaning device embodying the improvements of the present invention therein.

Fig. 2 is a central, vertical section of the same.

Fig. 3 is a side view of one of the outside brushes, showing its attachment to a bell-crank form of mounting lever.

Fig. 4 is a cross-section on line 4—4 in Fig. 3, illustrating the construction of the brush and the manner of mounting it in the bell-crank lever.

Referring more in detail to the drawings:

In its present preferred form of construction, the device comprises a circular metallic and horizontally disposed base member 10, to the under side of which there is fitted and secured a rubber disk 12 of substantial diameter, serving as a suction cup element whereby the device may be held secure while in use upon a flat surface. Formed centrally on the base member is a boss 13

in which a short tubular guide member 14 is fixed. This member extends a short distance above the boss, as noted best in Fig. 2.

Slidably contained in the tubular guide 14 is a sleeve 15, held against rotative movement in the guide and its vertical movement limited by means of a pin or stud 16 fixed on the sleeve and extended into a vertical slot 17 formed in the upper end portion of the tubular member 14. At its upper end, the sleeve 15 has a directly outwardly turned flange 18 for a purpose presently understood.

Fitted securely in the sleeve 15 is the lower end portion of a vertical stem or standard 20, of wood or other suitable material, mounting a bristle brush 21 along its upper end portion. This brush is shaped to conform to the inside of a drinking glass when the glass is placed thereover for cleaning, as shown in Fig. 2. At its upper end, the standard mounts a tuft of bristles 24 for brushing or cleaning the inside surface of the bottom of the glass as applied thereto.

Extending upwardly from the peripheral portion of the base 10, at equally spaced intervals thereabout, are standards 25. Mounted pivotally upon each of these standards is a bell-crank lever comprising a substantially horizontally directed arm 26x and an upright arm 26y. The arms 26x extend radially from the brush standard 20 and are pivotally mounted intermediate their ends by pivot pins 28. At their inner ends they engage against the under side of the flange 18 of sleeve 15 as noted in Fig. 2. The arms 26y extend upwardly from the outer ends of arms 26x beyond the points of pivotal support of the levers by the pivot pins 28. The arms 26y are of channel form in cross-section as seen in Fig. 4. Each of these arms mounts a brush 29 of foam or sponge rubber, for wiping the outside and rim surfaces of a glass when applied to the device as indicated in Fig. 2.

Each brush 29 comprises an elongated block of the selected material. Its outer longitudinal portion is contained between sheets of stiff rubber 30—30, or the like, as seen best in Fig. 4. These, in turn, are fitted in a U-shaped brush back 31 of metal, and the said back 31 is contained in the inwardly faced channel-shaped arm 26y of the supporting bell-crank.

It is noted that the various brushes 29 are pivotally fixed in the arms of their respective levers by horizontal pivots 35 extended through the upper ends of the arms 26y and through the brush backs 31 at points medial of the upper and lower ends of these brush backs. The brushes

are thereby held for pivotal action in the channel-shaped arms 26y but can tilt as necessary to allow the rubber brushes to conform to the slope of the walls of the glass.

A coiled spring 40 is located under compression about the sleeve 15, to bear at its lower end against the base 10 and at its upper end against the inner end portions of the bell-crank arms 26x. The spring operates to yieldingly retain the bell-crank levers 26y outwardly inclined, for example as shown in dotted lines in Fig. 2, thus to hold the brushes 29 outwardly and away from the bristle brush. However, when a glass, such as indicated at 50, is placed in an inverted position over the bristle brush, and a downward pressure applied, the bristle brush, through pressure of the glass, will be moved downwardly against the pressure of the spring 40 and force will be applied through the flange 18 of sleeve 15 against the inner ends of arms 26x to cause all bell-crank arms 26y to swing inwardly, thus to press the brushes 29 against the outside surface of the glass. Then, by a rotative turning of the glass as held in the hand, the glass will be brushed both inside and outside. When downward pressure against the glass is removed, the spring 40 restores the parts to normal position.

With the parts so constructed and assembled, the use of the device is as follows:

First, the device is set in a pan or basin of wash water, the water level coming approximately up to the top of the brushes. A glass to be washed is grasped by its lower end and applied in an inverted position, directly over the bristle brush, and is pressed downwardly until the bell cranks are all actuated to swing the rubber brushes 29 against the outer surface of the glass as in Fig. 2. Then the glass is rotated by hand back and forth through an arc of about 120 degrees, and is thereby brushed both inside and outside. The glass is then lifted off and may or may not be further rinsed.

An important feature of the invention resides in the extending of the outside brushes 29 downwardly to such extent that they will terminate below the level of the rim of the glass as applied to the device for washing. Thus, when the soft rubber brushes are swung inwardly, the material thereof will be pressed tightly into contact with the wall of the glass as indicated in Fig. 4, and also against the rim of the glass, and due to its pressure against the rim, will curl upwardly and against the inside of the rim surface, thus to effectively contact all surfaces of the rim with cleaning effect when the glass is rotated.

Having thus described my invention, what I claim as new therein and desire to secure by Letters Patent is:

1. A glass cleaning device comprising a base, an upwardly extending guide member fixed thereon, an inside brush mounted vertically by said guide member for limited up and down movement thereon and adapted to receive a drinking glass

thereover in an inverted position for cleaning its inside by rotative movement of the glass, a plurality of bell crank levers pivotally mounted on the base, outwardly from and at intervals spaced about the said brush, each having a horizontally directed arm extended to adjacent the brush and an upwardly extending arm, outside brushes mounted by the said upwardly extended arms in positions to be engaged with the outside surface 10 of a glass as applied for cleaning over the first mentioned brush, and means on the inside brush for engaging and moving the inner ends of the horizontally directed arms of the bell cranks downwardly for the actuation of the bell cranks in a manner to cause the outside brushes to be moved by the upwardly directed arms against the glass.

2. A glass cleaning device as recited in claim 1 including also a spring mounted on the base and bearing against the horizontal arms of the bell cranks to yieldingly and normally retain the bell cranks in a position at which the outside brushes are spaced outwardly from the inside brush.

3. A glass cleaning device of the character described comprising a base, a rigid, tubular guide member extended upward therefrom, an inside brush adapted to receive a drinking glass thereover in an inverted position for cleaning the inside of the glass, said brush having a mounting standard fitted at its lower end in said tubular guide member for limited up and down movement, a plurality of bell crank levers pivotally mounted on the base, outwardly from and at intervals spaced about the brush standard, each having a horizontally directed arm extended inwardly from the pivoted support to adjacent the brush standard, and an upwardly directed arm, outside brushes mounted by the said upwardly directed arms in positions to extend along and to be engaged against the outside surfaces of a glass as applied over the inside brush for cleaning, an annular flange on the brush standard for engaging the said horizontally directed arms for their downward actuation to cause the outside brushes as mounted by the upwardly directed arms to be moved against the outside surface of the glass, and a coiled spring disposed under compression about the tubular guide, bearing against said base and said horizontal arms of the bell cranks to normally retain the outside brushes spaced outwardly from the inside brush.
